CLAIM

The ornamental design for an elevated paving stone, as shown and described.

DESCRIPTION

FIG. 1 is a perspective view of an elevated paving stone design according to the present invention.

FIG. 2 is a front elevational view thereof.

FIG. 3 is a rear elevational view thereof.

FIG. 4 is a top view looking down thereof.

FIG. 5 is a bottom view looking up thereof.

FIG. 6 is a side elevational view thereof.

FIG. 7 is a perspective view of a second embodiment of an elevated paving stone design according to the present invention.

FIG. 8 is a front elevational view of the second embodiment thereof.

FIG. 9 is a rear elevational view of the second embodiment thereof.

FIG. 10 is a top view of the second embodiment looking down thereof.

FIG. 11 is a bottom view of the second embodiment looking up thereof.

FIG. 12 is a side elevational view of the second embodiment thereof.

FIG. 13 is a perspective view of a third embodiment of an elevated paving stone design according to the present invention.

FIG. 14 is a front elevational view of the third embodiment thereof.

FIG. 15 is a rear elevational view of the third embodiment thereof.

FIG. 16 is a top view of the third embodiment looking down thereof.

FIG. 17 is a bottom view of the third embodiment looking up thereof.

FIG. 18 is a side elevational view of the third embodiment thereof.

FIG. 19 is a perspective view of a fourth embodiment of an elevated paving stone design according to the present invention.

FIG. 20 is a front elevational view of the fourth embodiment thereof.

FIG. 21 is a rear elevational view of the fourth embodiment thereof.

FIG. 22 is a top view of the fourth embodiment looking down thereof.

FIG. 23 is a bottom view of the fourth embodiment looking up thereof; and,

FIG. 24 is a side elevational view of the fourth embodiment thereof.
